(57) **CLAIM**

The ornamental design for a display screen or portion thereof with animated graphical user interface, as shown and described.

DESCRIPTION

FIG. 1 is a front view of a first image of a display screen or portion thereof with animated graphical user interface showing my new design; and,
FIG. 2 is a second image thereof.

The appearance of the graphical user interface sequentially transitions between the images shown in FIGS. 1 and 2. The process or period in which one image transitions to another forms no part of the claimed design. The dash-dash-dash lines illustrate text, icons, or the remainder of the graphical user interface and form no part of the claimed design. The dash-dot-dash lines depict a boundary line of a display screen or portion thereof, and form no part of the claimed design.
